ATTORNEY

UNITED STATES PATENT OFFICE

2,355,990

ALTIMETER

Anton Menzer, Brooklyn, N. Y., assignor of one-half to Adolf Fischer, Brooklyn, N. Y.

Application April 30, 1941, Serial No. 391,135

1 Claim. (Cl. 73—4)

This invention relates to a new and useful sensitive altimeter, particularly intended for indicating altitudes in aircraft, and it is one of the objects of my invention to provide such an altimeter using one hand or pointer only to permit at a glance a more direct reading of the altitudes in thousands and multiples thereof, and thus doing away with the use of two hands or pointers, and the calculations based on their various indications necessitated thereby, thus positively avoiding eventually disastrous errors caused by errors in these calculations.

Still another object of my invention is the provision of an altimeter of comparatively simple and inexpensive construction, yet durable and highly efficient in operation.

A further object of my invention is the provision of a sensitive altimeter provided with means to prevent any disturbances in its operation, caused for instance by back-lash or the like.

A still further object of my invention is the provision of an altimeter of this type having its diaphragm equipped with various means for compensating the influences of changes in temperature on the diaphragm.

These and other objects and advantages of my invention will become more fully known as the description thereof proceeds and will then be more specifically defined in the appended claim.

In the accompanying drawing forming a material part of this disclosure:

Fig. 1 is a sectional side elevation of an altimeter constructed according to my invention.

Fig. 2 is a section on line 2—2 of Figure 1.

As illustrated, in the casing 48 a frame 49 is arranged in which a spindle 50 is rotatably journaled to be operated by means of knob 51 or the like from the outside of the casing.

The lower end of spindle 50 carries a gear 54 located below a lower branch 53 of frame 49. The gear 54 meshes with a gear 55 secured to the lower end of a threaded rod 56 journaled in the branch 53. A flanged nut 58 is threaded on rod 56. The flange of nut 58 has an opening through which extends a guide rod 57 which is secured at its lower end in branch 53. The guide rod 57 prevents the nut 58 from turning when the threaded rod 56 is rotated. A portion of the flange on nut 58 extends in a groove within collar 59 or the like carried by a pinion 61 rotatably journaled on a shaft 60. The shaft 60 is journaled at its lower end in branch 53, and at its upper end in another branch 63 of frame 49. The shaft 60 is provided with a spiral groove 62 along its outer face. Two pins 60' and 60'' secured to

pinion 61 travel in spiral groove 62 during upward and downward movement of the pinion. If the spindle 50 be turned clockwise or anticlockwise, the gear 54 in mesh with gear 55 will turn threaded rod 56 causing the flanged nut 58 to be elevated or lowered, and by reason of the flange of the nut extending into the groove of collar 59 to likewise elevate or lower the pinion 61. The pins 60' and 60'' of pinion 61 will travel along the spiral groove 62 of shaft 60 and turn the same. A gear 64 is secured to the shaft 60 near its upper end. This gear is in mesh with a pinion 71 secured to a shaft 72 journaled at its lower end in a bearing 73 and near its upper end in a frame member 73'. The upper end of shaft 72 carries an indicator hand movable over a suitable graduated dial 31.

The spindle 50 carries above the branch 63 of frame 49 a smaller gear 65 in mesh with a gear 66 on a staff 67 journaled in an arm of the frame member 73'. The staff 67 carries a disc 68 whose upper surface carries graduations representing barometric pressure readings and adapted to register with a suitable index mark. These graduations are viewable through an opening 69 in dial 31 and a transparent closure plate 70 for casing 48.

Below the dial 31, the shaft 72 carries a gear 74 in mesh with the gear teeth on the periphery of disc 28. The upper surface of disc 28 carries graduations with suitable numbers representing thousands of feet or meters of altitude. These indicia are viewable through an opening 32 in dial 31 and the transparent closure plate 70.

A staff 75 is journaled at its lower end in a bearing 76 of the casing and at its upper end in bearing 73. In order to provide temperature compensation at the zero indication of the altimeter, a bi-metallic strip 77 or the like is engaged with the staff 75 by means of suitable fastening means 78, 79 connected by means of a member 80. The other end of the strip 77 is connected, as shown in Figure 2, by means of a link or rod 81 also of bi-metal to the diaphragm arrangement generally designated 82. A gear sector 83 is attached to shaft 75 which meshes with pinion 61 for actuation of the same when the shaft 75 is turned. A hair spring 83' is fastened to a post 84 at one end, and with its other end engages the shaft 60.

The device operates as follows:

If an airplane flies from a place of higher elevation to one of lower elevation, or vice-versa, the dial indicating the barometric pressure is set by the proper manipulation of the knob 51, and

spindle 50 to indicate the barometric pressure prevailing at the place of destination, as per advice received from said place. By turning the spindle 50 clockwise or anticlockwise, the gear 54 which is in mesh with gear 55 will turn the threaded rod 56 and cause the flanged nut 58 to be elevated or lowered and because the flange of the nut extends into the groove of the collar 59 the pinion 61 will elevate or lower the same as the case may be. Consequently, as the pins 60' and 60'' of the pinion travel in the spiral groove 62 of the shaft 60, the same will be turned to turn gear 64. In the meantime, the spindle 50 carrying a small gear 65 which is in mesh with a gear 66 on the staff 67 which carries a disc 68 whose upper surface carries graduations representing barometric pressure readings adapted to register with a suitable index mark, and in this manner the disc 68 can be turned to indicate the barometric pressures prevailing. These indications are then visible through the opening in the dial 31 and the transparent closure plate 70. As now the gear 64 is in mesh with a pinion 71 secured to the shaft 72 the lower end of which is journaled in a bearing 73 in which is also journaled the upper end of a staff 75 the lower end of which is journaled in a bearing 76 of the casing for the device, and a bimetallic strip 77 is connected to staff 75 by means of a member 80 at one end while its other end is connected by a bi-metallic link 81 to a diaphragm arrangement 82 responding to any changes in the barometric pressure by the intermediary of the connection 83 with the pinion 61, the rotation of pinion 71 will impart to shaft 72 a rotary motion, and as the same carries below dial 31 a gear 74 in mesh with the gear teeth on the periphery of the disc 28, the upper surface of which carries graduations with suitable numbers representing thousands of feet or meters altitude, which become visible through the opening 32 in dial 31 and the transparent closure plate 70 and any changes in altitude will be indicated commensurate to the changes in barometric pressures prevailing at these altitudes.

It will be understood that I have described and shown the preferred form of my invention, and that I may make such changes in its general ar-

rangement and in the construction of its minor details as come within the scope of the appended claim without departure from the spirit of the invention and the principles involved.

5 Having thus described my invention, what I claim as new, and desire to secure by Letters Patent is:

A settable altimeter comprising a casing, a frame in said casing having upper and lower branch arms, a spindle extending from outside the casing and journaled in said branch arms, a hand knob on the spindle outside the casing, a train of gears operatively connected to the spindle adjacent the lower branch arm, a shaft having 10 a spiral groove journaled in said upper and lower branch arms, a pinion slideable on said shaft, a collar having a groove on said pinion, pins on said pinion engaging said spiral groove for travel therealong, a threaded rod journaled in the lower 15 branch arm and rotatable by said train of gears, 20 a flanged nut on said rod engaging with its flange the groove of said collar to elevate and lower said pinion during rotation of said threaded rod, a guide rod secured to the lower branch arm and 25 extending through an opening in the flange of said nut for preventing the nut from rotating when the threaded rod is rotated by the spindle through said train of gears, a gear secured to the spirally grooved shaft near its upper end, an indicator shaft mounted in said casing carrying a 30 gear in mesh with the gear on said spirally grooved shaft, a pointer carried by the indicator shaft, a graduated main dial over which said pointer is movable, an aneroid diaphragm mounted 35 in said casing, motion transmission mechanism operatively connecting said aneroid diaphragm and said pinion to rotate the latter, said main dial having an opening therein, a dial bearing barometric graduations back of said main 40 dial and visible through said opening carried by a stub shaft mounted in said casing, a gear on said stub shaft, a gear on said spindle in mesh with the gear on the stub shaft whereby the dial bearing barometric graduations will indicate 45 through the opening in the main dial the barometric pressure for which the altimeter is set.

ANTON MENZER.
